UNITED STATES PATENT OFFICE

2,550,300

WINDOW GLASS MOUNTING

Joseph Schunk, Union, N. J., assignor to The
National Lock Washer Company, Newark, N. J.

Application October 25, 1945, Serial No. 624,395

2 Claims. (Cl. 20—56.4)

1
This invention relates to an improvement in the means for mounting glass, or sometimes referred to as a panel, in a frame.

In certain prior art structures where a resilient glazing strip has been used it has been necessary to disassemble some part of the frame in order to assemble the glass pane or panel with the glazing strip. Other types of panel mountings have been proposed which have been more or less complicated both as to the construction of the frame per se as well as the glazing strip. Therefore the principal object of my invention is to provide a construction which will eliminate the above objections.

Another object of my invention is to provide a mounting for the glass or panel wherein the construction of the frame is simplified as well as the construction of the glazing strip and hence the total cost of the mounting is reduced. Another object of my invention is to provide a construction which simplifies the assembly operations and hence reduces the cost of assembly and disassembly. These and other objects will be apparent to one skilled in this particular art from a study of the annexed drawings, wherein:

Figure 1 is a sectional view through a portion of a frame and panel.

Figure 2 is a view similar to 1 but showing a slight modification thereof.

Figure 3 is a view similar to Figure 1 but of a further modified but preferred form of my improvement.

Figure 4 is a view of Figure 3 showing the ease of assembly and disassembly of the construction shown in Figures 1, 2 and 3.

In the various views wherein like numbers refer to corresponding parts, 1 is a frame having an upwardly extending portion 2 which acts as a support for backing strip 3. The backing strip 3 has a projecting rib 4 which forms a seat for the pane or panel 5 which also engages the backing member 3 which is made of a suitable resilient material. Extending from the portion 2 is a shelf 6 for carrying the backing member 3 which may be held to the shelf 2 by any suitable means such as a dovetail construction 7 or the part 2 may have an inturned flange 8 as shown in Figure 2 for holding the backing member 3 in position during assembly of the pane 5. Frame 1 has a member 9 extending in the same general direction as the portion 2 and terminates in a ledge 10 which is adapted to fit a longitudinal recess 18 in the glazing strip 11 that is made of suitable resilient material such as rubber. The longitudinal recess 18 is preferably of

2
a size such that the heel 13 of the glazing strip 11 will contact with a portion 14 of the frame after the installation is completed. Connecting the shelf 6 with the portion 9 is a portion 12 and as shown in Figure 3 this portion is at an obtuse angle with respect to the shelf 6 for a purpose that will presently be pointed out. In Figures 1, 2 and 4 the portion 12 is shown as being substantially parallel with the parts 2 and 9.
10 It will be noted from the various figures that the glazing strip 11 is made quite arcuate with its heel portion 13 resting on a portion 14 of the frame and normally contacting along the surface 19 with the pane 5 there being no intermediate contact of the concave side of the glazing strip 11 with any part of the frame or the pane where the glazing strip passes through the opening 16 leading to the trough 17 within which the heel 13 of the glazing strip 11 is positioned.
15 This provides a construction which is easy to assemble and disassemble since an assembly tool 15 may be inserted over the ledge 10 into the longitudinal recess adapted to receive the ledge 10 after assembly and the glazing strip can be readily forced into a position approximately as shown in Figure 4 and then readily forced downwardly on the slanting surface 12 shown in Figure 3. It will be noted from Figure 3 of the drawing that the inner concave surface of the glazing strip extends in an unbroken surface from end to end and terminates at the bottom 14 of the trough 17, having the side walls 12 and 9, adjacent the end of the slanting surface 12 and that the slanting surface 12 joins the bottom of trough 17 in a line beyond the plane of the pane or panel. Also the outer surface of the glazing strip is convex from end to end and only interrupted by the longitudinal recess 18. The slanting surface 12 acts to increase the tension of the glazing strip against the pane or panel, as the strip is forced into holding position. It also enhances at least the disassembly operation of the pane or panel from the frame.

What I claim is:

45 1. A window panel mounting comprising a frame having a backing portion and a shelf extending therefrom, a backing member of resilient material carried by the shelf with means for holding it on the shelf, the backing member having one side engaging said backing portion of the frame while the other side engages one side of a panel and a seat portion to receive the edge of the panel, the frame having a trough formed by two spaced walls joined by a bottom member, one wall extending in an outwardly slant-

ing direction away from the panel seat and joining the bottom of the trough on a line beyond the plane of the pane or panel while the other wall extends in the same general direction as said backing portion of the frame and terminates in a ledge, a glazing strip of resilient material having a concave inner surface and a convex outer surface from end to end, one end terminating at the bottom of the trough adjacent the end of said slanting surface while the other end is adapted to engage the panel to hold it against said backing member, the strip having a groove in the convex surface to receive said ledge for holding the strip in operative position.

2. A window panel mounting including a frame of suitable material having a upwardly extending portion, a shelf extending from said portion intermediate its ends, a member of resilient material having one part located on said shelf and acting as a seat for said panel while another part extending upwardly along said extending frame portion and acting as a backing member for said panel, means coacting with the shelf and said resilient member for holding the member in place on the shelf, said frame having a part extending downwardly from the end of the shelf opposite to said upwardly extending portion of the frame, said downwardly extending part being formed at its terminus in a direc-

tion similar to that of said shelf and then turning upwardly terminating in a ledge and forming the outer wall of a trough, a glazing strip of resilient material having a continuous concave inner surface and a convex outer surface from end to end, one end terminating at the bottom of the trough while the other end is adapted to engage a panel to hold it against said backing member, the strip having a groove in the convex surface to receive said ledge for holding the strip in operative position.
